UNITED STATES PATENT OFFICE.

WILLIAM WHARTON, JR., AND VICTOR ANGERER, OF PHILADELPHIA, PENNSYLVANIA, ASSIGNORS TO WILLIAM WHARTON, JR., & COMPANY, INCORPORATED, OF PHILADELPHIA, PENNSYLVANIA, A CORPORATION OF PENNSYLVANIA.

RAILWAY-FROG STRUCTURE.

SPECIFICATION forming part of Letters Patent No. 690,336, dated December 31, 1901.

Application filed October 10, 1901. Serial No. 78,200. (No model.)

To all whom it may concern:

Be it known that we, WILLIAM WHARTON, Jr., and VICTOR ANGERER, citizens of the United States, and residents of Philadelphia, Pennsylvania, have invented certain Improvements in Railway-Frog Structures, of which the following is a specification.

The object of our invention is to make a substantial railway-frog in which a hard-metal section is used in connection with the ordinary rails of a railway. This object we attain by allowing the hard-metal portion, which forms the point and the side-bearing portions of the frog, to overhang the wing-rails, as fully described hereinafter.

In the accompanying drawings, Figure 1 is a plan view of a railway-frog, illustrating our invention. Fig. 2 is a transverse section on the line 22, Fig. 1. Fig. 3 is a transverse section on the line 33, Fig. 1. Fig. 4 is a perspective view of the hard-metal portion. Fig. 5 is a plan view of a modified form of the structure shown in Fig. 1. Fig. 6 is a transverse section on the line 66, Fig. 5. Fig. 7 is a transverse section on the line 77, Fig. 5. Fig. 8 is a transverse section on the line 88, Fig. 5. Fig. 9 is a transverse section showing a further modification of the invention.

A is the hard-metal portion, which is preferably made of manganese steel. This hard-metal portion has a point a and side-bearing flanges a'a', separated from the point by the grooves c c. The rails B B' are secured to the tongue a², extending from one end of the hard-metal portion A.

D D' are rails in line with the rails B' and B, respectively, and are bent out, forming wing-rails D² D³. The heads of the wing-rails D² D³ are cut away, as shown in the transverse sectional views, Figs. 2 and 3, and the side-bearing flanges a'a' of the hard-metal portion A extend above the cut-away portions of the rails D² D³ and overhang said rails. Lips a³ a³ depend from each side of the hard-metal section A, and thus extend downwardly outside of the rails D² D³, respectively. The base of the hard-metal section A rests upon the base-flanges of the wing-rails D² D³, as

shown, so that when the transverse bolts E are passed through the wing-rails and the hard-metal section and the nuts e screwed up tight the hard-metal section is rigidly secured to the rails. Longitudinal reinforcing-bars F may be used between the head and the base-flange of the rails D² D³, as shown in Figs. 2 and 3, in order to strengthen them, if desired. The inner edges of the bearing-flanges a'a' are in line with the inner edges of the rails D² D³, respectively, and these rails are preferably beveled at d, so as to widen the throats at c', and the vertical joints between these bearing-flanges and the rails are preferably at an angle, as shown at i i and i' i'.

The hard-metal section A may be secured to the rails by any desired number of transverse bolts or by other fastening devices, if preferred.

In Figs. 5, 6, and 7 we show a modification in which the outside depending lips of the hard-metal portion A are continued downwardly, forming deep flanges a⁴ a⁴, which extend to and rest upon the outside base-flanges of the rails D² D³, respectively. This construction can be used when it is desired to more rigidly support the outer edges of the hard-metal portion A. In this case openings f f are made in the depending flanges a⁴ a⁴ to allow for the reception of the heads and nuts of the transverse bolts E. Washers e' are preferably used, so that the nut e need not pass into the recess.

In Fig. 9 we show two hard-metal portions A' A', with outside depending flanges overlapping the wing-rails and resting upon the flanges thereof, and an independent point-section A², separated from the sections A' A' by spacing-blocks C C. In this instance the outside depending flanges a⁶ a⁶ not only rest upon the base-flanges of the rails D² D³, but extend outside of them down to a level with the bottom of the rails and rest upon the ties also.

If the frog is intended to be used at a place in the track where the travel over it is greater on one of its sides than the other, then in such case the hard-metal section may be made to

overlap only the one wing-rail carrying the greater travel, while the head of the other wing-rail may remain uncut and of its full normal size and section.

5. We claim as our invention—

1. The combination in a railway-frog, of the track-rails, one pair of said track-rails being extended to form wing-rails, said wing-rails having portions of their heads cut away, 10 with a metallic section extending above the cut-away portion of the wing-rails, substantially as described.

2. The combination in a railway-frog, of the track-rails, wing-rails having their heads 15 cut away and a hard-metal section mounted between the wing-rails and secured to the track-rails and to the wing-rails and overlapping the wing-rails, substantially as described.

20 3. The combination in a railway-frog, of the track-rails, wing-rails and a hard-metal section having a point and bearing-flanges, the heads of the wing-rails being cut away, and the said hard-metal section extending 25 over the reduced portions thereof and having depending lips outside of the said reduced portions, substantially as described.

4. The combination in a railway-frog, of the track-rails, wing-rails and a hard-metal

section having a point and bearing-flanges, 30 the heads of the wing-rails being cut away, and the said hard-metal section extending over the reduced portions thereof and having depending flanges outside of the wing-rails which extend downward to and rest upon the 35 base of said wing-rails, substantially as described.

5. The combination in a railway-frog, of the track-rails, the frog-point, the wing-rails, the heads of said wing-rails being reduced in 40 height, and a hard-metal section or sections extending over the reduced portions of the wing-rails, substantially as described.

6. The combination in a railway-frog, of the track-rails, one of said track-rails being 45 extended to form a wing-rail, the head of said wing-rail being cut away, with a metallic section extending above the cut-away portion of said wing-rail, substantially as described.

In testimony whereof we have signed our 50 names to this specification in the presence of two subscribing witnesses.

WILLIAM WHARTON, JR.
VICTOR ANGERER.
